ROLL CRIMPING MACHINE

Harry Christopher Bryans, Three Rivers, Quebec, Canada, assignor to Canadian International Paper Company, Montreal, Quebec, Canada, a corporation of Quebec

Application March 10, 1952, Serial No. 275,820

5 Claims. (Cl. 53—150)

1

This invention relates to new and useful improvements in roll crimping machines generally and particularly seeks to provide novel crimping devices for such machines.

This invention is an improvement on roll crimping machines of the type disclosed in U. S. Patent 2,533,993, granted to H. C. Bryans on December 12, 1950.

It is an object of this invention to provide a novel crimping machine particularly suitable for crimping the ends of the wrappers on various sizes of rolls of paper such as newsprint and in which the paper roll is supported on a pair of driven carrier rolls, one of which is fitted with a pair of adjustably mounted crimping assemblies.

Another object of this invention is to provide a machine of the character stated which crimps and wraps the wrapper ends by two successively applied crimping actions at each point of contact of the crimpler elements with the projecting paper wrapper to effectively smooth each pleated or crimped wrapper segment before formation of the next following pleat or crimp has been started.

Another object of this invention is to provide a machine of the character stated which has fixed crimpler elements and movable crimpler elements, the latter being operable through cam follower and linkage connections actuated by serial contact with that carrier roll which does not carry the crimping assemblies.

A further object of this invention is to provide a machine of the character stated which is simple in design, rugged in construction and economical to manufacture.

With these and other objects in view, the nature of which will be more apparent, the invention will be more fully understood by reference to the drawings, the accompanying detailed description, and the appended claims.

In the drawings,

Fig. 1 is a top plan view of a roll crimping machine containing crimping assemblies constructed in accordance with this invention;

Fig. 2 is an enlarged fragmentary top plan view showing one end of the machine in greater detail;

Fig. 3 is an enlarged transverse section taken along line 3—3 of Fig. 1; and

Fig. 4 is a perspective view of the roll crimping machine with a wrapped and crimped roll of paper in position thereon.

Referring to the drawings in detail, the invention as illustrated is embodied in a roll crimping machine including a plain carrier roll 10 and a

2

slotted carrier roll 11 rotatably mounted in spaced parallel relationship immediately below the level of the finishing room floor in a paper mill. The rolls 10 and 11 are gear driven from any suitable source of power. An ejector roller 12 suitably operated by a hydraulic or air cylinder (not shown) is located between the two rolls and serves to eject the finally crimped roll of paper from the carrier rolls.

Each end of the slotted carrier roll 11 is provided with a collar 13 slidably mounted thereon and operatively connected through slots 14 to collars threadably engaged with opposite end portions of an adjusting screw 15. It will be appreciated that the opposite ends of the screw 15 are threaded with opposite hand threads in order that rotation of the screw 15 in either direction will serve to move the collars 13 towards or away from each other. One end of the adjusting screw 15 extends beyond its associated carrier roll 11 and carries a hand wheel 16 and locking wheel 16a usable to adjust the spacing between the collars 13.

A sleeve 17 is also slidably mounted adjacent each end of the slotted carrier roll 11 and is located inboard of the associated collar 13 and provides the supporting means for the crimpler elements which will hereinafter be described in detail. Each collar 13 is provided with a plurality of lugs 18 which are disposed in alignment with corresponding lugs 19 formed integral with the sleeve 17. Each of the lugs 18 has rigidly affixed thereto a stud 20 which carries a compression spring 21 interposed between the lugs 18 and 19 to resiliently bias the sleeve 17 away from the collar 13. Suitable lock nuts 22, 22 are provided on the projecting end of the stud 20 in order to provide an abutment limiting the movement of the sleeve 17 away from the collar 13 and to provide for adjustment of the effective force which the spring 21 can apply.

Firmly attached to each sleeve 17 is a plurality of generally quadrilateral mounting plates 23. Each mounting plate carries a crimpler assembly but only one such will be here described as they are all identical. A short connecting link 24 is pivotally attached to the sleeve 17 through a lug or boss 25, as shown in Fig. 3. The free end of the short link 24 is bifurcated as at 26 and is pivotally connected to and adjacent the end of a long two-piece connecting link generally indicated at 27. The link 27 includes a leading section 28 and a follower section 29 overlapping each other and being provided with slots 30 so as to be adjustably secured by bolts 31. The leading sec-

tion carries a cam follower 32 at its free end. The follower section 29 has a bifurcated end 33 pivotally connected to the free end of a short rocker arm 34 secured to one end of a pivot stud 35 which in turn is rotatably mounted in and extends through a bearing boss 36 and the outer following corner of the associated mounting plate 23. Securely mounted to the rear end of the pivot stud 35 and behind the mounting plate is a long rock arm 37 disposed in alignment with the arm 34. The extended end portion of the rock arm 37 is firmly attached to the face of an elliptically shaped movable crimping element 38. Firmly attached to the mounting plate 23 on the rear side thereof is a semi-oval fixed crimping element 39 provided with an elliptically shaped cut-out portion on the trailing edge portion adapted to receive the movable crimping element. A tension spring 40 is attached between a stud 41 carried on the follower section 29 and a lug 42 carried on the sleeve lug 19.

The operation of the crimping mechanism is continuous with rotation of the positively driven carrier rolls. As shown in Fig. 3, the carrier rolls are driven clockwise, thus moving the paper roll counterclockwise. The plurality of crimping elements bodily moves clockwise with the slotted carrier roll. The fixed or leading crimping element 39 first makes contact with the extended roll wrapper, immediately crimping a segment thereof against the roll end face and then continuing on to wipe the crimped section against the roll end through the overlapping arcs of the crimper and the paper roll. However, just before the fixed crimper moves off the roll and before the succeeding crimper is making contact at a new succeeding point on the extended roll wrapper the cam follower 32 comes in contact with the plain carrier roll 40. This forces the movable crimping element 38 outwardly away from the fixed crimping element 39 in a quick stroke over the newly crimped segment to a point just in front of the next succeeding fixed crimper just as the latter is making its initial contact with the roll wrapper. Then the cam follower breaks contact with the plain carrier roll and the tension spring 40 retracts the movable crimping element to its resting position adjacent the fixed crimper. The next crimping unit repeats the action, of course, but at a succeeding point on the periphery of the roll. The degree of movement of the movable crimping element 38 may be varied by either shortening or lengthening the two-piece link 27.

The action of this crimping device very closely approximates the action formerly effected by manual operation with both hands. The movable crimping not only effects an additional wiping action to the newly crimped segment but assists in the initial crimping of the next succeeding wrapper segment.

Thus, this invention provides an improved crimping device for roll crimping machines which is capable of being used in connection with various sized paper rolls without tearing the wrapper and in a manner nearly duplicating manual crimping of roll wrappers.

It is, of course, to be understood that various details of arrangements and proportions of parts may be modified within the scope of the appended claims.

I claim:

1. In a machine for crimping the projecting ends of a wrapper over the ends of a roll of paper covered thereby wherein is provided a pair of carrier rolls for supporting a wrapped roll of

paper, means for positively driving said carrier rolls in the same direction, a pair of collars slidably mounted on one of said carrier rolls and means for positively adjusting the spacing between said collars; the combination of a plurality of two-part crimper elements connected to each of said collars, one part of each crimper element being relatively movable with respect to the other, and means for imparting cyclic movement to each such movable part during each revolution of the associated carrier roll.

2. In a machine for crimping the projecting ends of a wrapper over the ends of a roll of paper covered thereby wherein is provided a pair of carrier rolls for supporting a wrapped roll of paper, means for positively driving said carrier rolls in the same direction, a pair of collars slidably mounted on one of said carrier rolls and means for positively adjusting the spacing between said collars; the combination of a sleeve slidably mounted on said first mentioned carrier roll inwardly of each of said collars and resiliently connected thereto, a plurality of radially extending mounting plates rigidly affixed to each of said sleeves, a fixed crimper element rigidly secured to the inner face of each of said mounting plates, a movable crimping element operably associated with said fixed crimper element, and cam followers and linkages operably carried by said sleeve and said mounting plates and connected with said movable crimping elements to impart cyclic action thereto, said followers and linkages being so arranged as to have cyclic motion imparted thereto once during each revolution of the carrier roll upon which they are mounted as the result of contact of the cam followers with the adjacent carrier roll.

3. In a machine for crimping the projecting ends of a wrapper over the ends of a roll of paper covered thereby wherein is provided a pair of carrier rolls for supporting a wrapped roll of paper, means for positively driving said carrier rolls in the same direction, a pair of collars slidably mounted on one of said carrier rolls and means for positively adjusting the spacing between said collars; the combination of a sleeve slidably mounted on said first mentioned carrier roll inwardly of each of said collars and resiliently connected thereto, a plurality of radially extending mounting plates rigidly affixed to each of said sleeves, a fixed crimper element rigidly secured to the inner face of each of said mounting plates, a movable crimping element operably associated with said fixed crimper element, a pivot stud rotatably mounted in said mounting plate and having its ends extending beyond the faces thereof, a rock arm rigidly attached to the inner end of said pivot stud and having its free end rigidly affixed to said movable crimping element, a second rock arm rigidly attached to the outer end of said pivot stud in alignment with said first mentioned rock arm, a connecting link having one end pivotally connected to the free end of said outer rock arm and its other end provided with a cam follower, a second connecting link having one end pivotally connected to said first link adjacent the cam follower end thereof and its other end pivotally connected to said sleeve, and resilient means for constantly biasing said movable crimping element towards contact with said fixed crimper element, said connecting links being so proportioned that the cam follower end of said first mentioned connecting link will contact the other of said carrier rolls once during each revolution whereby to im-

part a single cycle of motion to said movable crimpler element.

4. In a machine for crimping the projecting ends of a wrapper over the ends of a roll of paper covered thereby wherein is provided a pair of carrier rolls for supporting a wrapped roll of paper, means for positively driving said carrier rolls in the same direction, a pair of collars slidably mounted on one of said carrier rolls and means for positively adjusting the spacing between said collars; the combination of a sleeve slidably mounted on said first mentioned carrier roll inwardly of each of said collars and resiliently connected thereto, a plurality of radially extending mounting plates rigidly affixed to each of said sleeves, a fixed crimpler element rigidly secured to the inner face of each of said mounting plates, a movable crimpler element operably associated with said fixed crimpler element, a pivot stud rotatably mounted in said mounting plate and having its ends extending beyond the faces thereof, a rock arm rigidly attached to the inner end of said pivot stud and having its free end rigidly affixed to said movable crimpler element, a second rock arm rigidly attached to the outer end of said pivot stud in alignment with said first mentioned rock arm, a connecting link having one end pivotally connected to the free end of said outer rock arm and its other end provided with a roller cam follower rotatably mounted thereon, a second connecting link having one end pivotally connected to said first link adjacent the cam follower end thereof and its other end pivotally connected to said sleeve, and resilient means for constantly biasing said movable crimpler element towards contact with said fixed crimpler element, said connecting links being so proportioned that the cam follower end of said first mentioned connecting link will contact the other of said carrier rolls once during each revolution whereby to impart a single cycle of motion to said movable crimpler element.

5. In a machine for crimping the projecting ends of a wrapper over the ends of a roll of paper covered thereby wherein is provided a pair of carrier rolls for supporting a wrapped roll of paper, means for positively driving said carrier rolls in the same direction, a pair of collars slid-

ably mounted on one of said carrier rolls and means for positively adjusting the spacing between said collars; the combination of a sleeve slidably mounted on said first mentioned carrier roll inwardly of each of said collars and resiliently connected thereto, a plurality of radially extending mounting plates rigidly affixed to each of said sleeves, a fixed crimpler element rigidly secured to the inner face of each of said mounting plates, a movable crimpler element operably associated with said fixed crimpler element, a pivot stud rotatably mounted in said mounting plate and having its ends extending beyond the faces thereof, a rock arm rigidly attached to the inner end of said pivot stud and having its free end rigidly affixed to said movable crimpler element, a second rock arm rigidly attached to the outer end of said pivot stud in alignment with said first mentioned rock arm, a connecting link having one end pivotally connected to the free end of said outer rock arm and its other end provided with a roller cam follower rotatably mounted thereon, a second connecting link having one end pivotally connected to said first link adjacent the cam follower end thereof and its other end pivotally connected to said sleeve, and resilient means for constantly biasing said movable crimpler element towards contact with said fixed crimpler element, said connecting links being so proportioned that the cam follower end of said first mentioned connecting link will contact the other of said carrier rolls once during each revolution whereby to impart a single cycle of motion to said movable crimpler element, said first mentioned connecting link being formed from two pieces adjustably secured together whereby to permit adjustment in distance between the pivotal connections thereof and to vary the amount of movement of said movable crimpler element during each cycle of operation thereof.

HARRY CHRISTOPHER BRYANS.
